US0D1100873S

(12) **United States Design Patent** (10) **Patent No.:** **US D1,100,873 S**
(45) **Date of Patent:** **** Nov. 4, 2025**

(54) **WIRELESS COMMUNICATION DEVICE**

(71) Applicant: **Samsung Electronics Co., Ltd.**, Suwon-si (KR)

(72) Inventor: **Hojae Lee**, Suwon-si (KR)

(73) Assignee: **Samsung Electronics Co., Ltd.**, Suwon-si (KR)

(**) Term: **15 Years**

(21) Appl. No.: **29/862,064**

(22) Filed: **Dec. 6, 2022**

(30) **Foreign Application Priority Data**

Oct. 5, 2022 (KR) 30-2022-0040648

(51) LOC (15) Cl. **14-03**

(52) U.S. Cl.

USPC **D14/188**; D14/155

(58) **Field of Classification Search**

USPC D14/240, 137, 140, 155, 188, 204, 265
CPC Y10S 370/913; H04W 52/0203; H04W

92/045; H04L 12/00; H04L 12/28

See application file for complete search history.

(57) **CLAIM**

The ornamental design for a wireless communication device, as shown and described.

DESCRIPTION

FIG. 1 is a front perspective view of a wireless communication device showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The broken lines in the figures depict portions of the wireless communication device that form no part of the claimed design.

1 Claim, 7 Drawing Sheets
